HOLDER FOR SANITARY COVERS FOR TOILET SEATS

Filed Sept. 17, 1929 2 Sheets-Sheet 2

UNITED STATES PATENT OFFICE

DANIEL J. KANN, OF EAU CLAIRE, WISCONSIN

HOLDER FOR SANITARY COVERS FOR TOILET SEATS

Application filed September 17, 1929. Serial No. 393,174.

This invention relates to sanitary covers for toilet seats, and more particularly to a holder for covers of this character.

The invention has for one of its objects to provide a holder of the character stated which shall be adapted to support the covers in extended or unfolded condition, so that the cover withdrawn therefrom may be easily and quickly applied to the seat.

10 The invention has for a further object to provide a holder of the character stated which shall be adapted to support the covers one in advance of the other or in tablet form and which shall be fully open at its front side, so as to permit a cover to be easily and quickly withdrawn therefrom.

15 The invention has for a further object to provide covers of the character stated with tabs which shall be adapted to extend beyond the holder and through the medium of which they may be withdrawn from the holder and applied to the seat.

20 The invention has for a further object to provide a holder of the character stated which shall be adapted to be supported in upright position at the rear end of the seat and with its open side facing the seat so as to permit the cover withdrawn therefrom to be easily and quickly applied to the seat.

25 The invention has for a further object to provide a support for the cover which shall be adapted to be secured to the toilet bowl and from which the holder may be removed to permit its supply of covers to be replenished.

30 The invention has for a still further object to provide a cover support which shall also be adapted to hingedly connect the seat to the bowl.

35 With the foregoing and other objects in view, the nature of which will appear as the description proceeds, the invention consists in the construction, combination and arrangement of parts hereinafter fully described and claimed, and illustrated in the accompanying drawings, wherein:—

Figure 1 is a view in side elevation of the sanitary cover holder applied to a toilet bowl;

50 Figure 2 is a view partly in front elevation

and partly in vertical section of the holder applied to the toilet bowl;

Figure 3 is a sectional view taken on a plane extending vertically through portions of the toilet bowl, seat, holder and holder supporting means;

Figure 4 is a top plan view illustrating the manner in which the holder supporting means is secured to the toilet bowl;

Figure 5 is a sectional view taken on a plane indicated by the line 5—5 of Figure 2;

Figure 6 is a sectional view taken on the line 6—6 of Figure 2, and

Figure 7 is a sectional view taken on the plane indicated by the line 7—7 of Figure 2.

Referring in detail to the drawings, 1 designates a toilet bowl, 2 the seat of the bowl, 3 the sanitary covers, 4 the holder for the covers and 5 the means for supporting the holder.

The sanitary covers 3, which are arranged in tablet form in the holder 4 and are supported by the holder in upright position at the rear end of the seat 2, are made of paper and are similar to the seat in contour. The covers 3 are provided with guard tabs 6, which extend into the openings 7 thereof, and they are provided with finger or pull tabs 8, which extend above the holder 4. The covers 3 are of such configuration that the one withdrawn from the holder 4 and applied to the seat 2 will cover the entire upper surface of the seat and the guard tabs 6 are so located on the covers that this part of the applied cover will extend downwardly through the seat and overlie the front portion of the bowl 1.

The holder 4 is made of metal and is similar to the covers 3 in contour. The covers 3 are provided with extensions 9 through the medium of which they are clamped in the holder 4.

The holder 4 is made of metal, and comprises a rear wall 10, which is similar to the covers 3 and their extensions 9 in contour. The holder 4 is provided with a straight bottom wall 11, which extends forwardly from the lower end of the rear wall 10 and

is provided at its front edge with an up-standing flange 12. The bottom wall 11, its flange 12 and that portion of the rear wall 10 located directly opposite the flange, constitute a channeled clamp in which the extensions 9 of the cover 3 are arranged. The holder 4 is provided with a top wall 13, and side walls 14 and 15, which extend forwardly from the top and side edges of the rear wall 10 and are similar in contour to the covers 3.

The side wall 14 is formed integrally with the top wall 13 and extends from the top wall to the bottom wall 11, the portion 14^a of this side wall closing one end of the channeled clamp. The side wall 15 is also formed integrally with the top wall 13 and terminates short of the channeled clamp, so as to leave the other end thereof open and to permit the extensions 9 of the covers 3 to be easily inserted into the channeled clamp. The top wall 13 is provided with an opening 16 through which the pull tabs 8 extend. The outer edges of the covers 3 contact with the top wall 13 and the side walls 14 and 15 of the holder 4, and they are supported within the holder by flanges 16, which extend forwardly from the rear wall 10 below the top wall and inwardly of the side walls. The flanges 16 extend through the opening 7 of the covers 3 and the inner edges of the covers contact therewith. The upper end of the flanges 16 are relatively spaced for the passage of the guard tabs 6. The covers 3 are also supported within the holder 4 by prongs 17, which extend forwardly from the rear wall 10 between the top wall 13 and flanges 16 and which pass through slots 18 in the covers. Cushions 19 are secured to the rear wall 10 by clamps 20, and they are located below the upper end portions of the flanges 16 and extend beyond the foremost cover 3.

The means 5 for supporting the holder 4 comprises plates 21 mounted upon the rear end portion of the bowl 1 and extending longitudinally of the bowl. The plates 21 are provided in their rear end portions with longitudinally extending slots 22 for the reception of bolts 23 by which they are secured to the bowl 1, the slots permitting the plates to be adjusted forwardly and rearwardly on the bowl.

The plates 21 are each provided with a pair of relatively spaced lugs or flanges 24, which receive the lower end portion of the holder 4, and the lugs or flanges are inclined to support the holder 4 at a slight upward and rearward inclination. The seat 2 is secured to the front ends of the plates 21 by double acting hinges 25, which permit the seat to be raised and lowered and to rest against the holder 4 when in raised position. The seat 2 contacts with the cushion elements 19 when in raised position, and in view thereof, it is maintained out of contact with the metal

parts of the holder 4 with the result that the surface thereof will not be marred.

From the foregoing description, taken in connection with the accompanying drawings, it will be understood that the supports 5 may be readily secured to the bowl 1, that the seat 2 may be readily secured to the supports, and that the holder 4 may be readily applied to and removed from the supports. As the front side of the holder 4 is fully opened, one of the covers 3 may be readily withdrawn therefrom and arranged upon the seat 2. The extension of the cover tabs 8 above the holder 4 enables one of the covers to be quickly grasped and withdrawn from the holder. After the covers 3 have all been used, a new tablet of covers may be readily placed in the holder 4, and this may be done with the holder remaining in position in its supports 5 or after the holder has been withdrawn from its supports. The tablet of covers may be provided with a back 3^a of cardboard or the like, and the covers may be secured to the back by fastenings 3^b which pass through the cover extensions 9 and through the back.

While I have described the principle of the invention, together with the structure which I now consider the preferred embodiment thereof, it is to be understood that the structure shown is merely illustrative and that such changes may be made, when desired, as fall within the scope of the invention as claimed.

I claim:—

1. In combination, a toilet bowl and its seat, hinges for the seat supporting means secured to the bowl at the rear edge of the seat, and formed integrally with the hinges of the seat, said supporting means comprising a pair of parallel upright members, a holder carried by said means and extending upwardly therefrom and having its front side open, a tablet of sanitary toilet seat covers arranged within the holder, and means permitting the covers to be withdrawn one at a time from the holder.

2. In combination, a toilet bowl and its seat, hinges for the seat supporting means secured to the bowl at the rear edge of the seat, said supporting means comprising a rearwardly extending plate integrally formed with the hinges, and a pair of up-standing spaced parallel members, a holder removably carried by said means and extending upwardly therefrom and having its front side open, a tablet of sanitary toilet seat covers arranged within the holder, the holder being provided at its upper end with an opening, tabs carried by the covers and extending through said opening, and means permitting the covers to be withdrawn one at a time from the holder.

In testimony whereof I hereunto affix my signature.

DANIEL J. KANN.
